UNITED STATES PATENT OFFICE.

DAVID LEVY, OF NEW YORK, N. Y.

AIRSHIP.

1,122,135.

Specification of Letters Patent. Patented Dec. 22, 1914.

Application filed August 12, 1913. Serial No. 784,330.

To all whom it may concern:

Be it known that I, DAVID LEVY, a subject of the Czar of Russia, residing at New York city, in the county of New York and State of New York, have invented new and useful Improvements in Airships, of which the following is a specification.

The general object of the invention is to refine the construction of that class of air-craft generally known as heavier-than-air, and to provide in such craft means for varying the altitude of the same, and eliminating the usual elevational planes, thus enabling the craft to ascend and descend in equilibrium. And to these ends the invention resides in a boat-shaped body depended from a series of receptacles adapted to function as air-cushions.

Other objects will appear and be better understood from that embodiment of my invention of which the following is a specification, reference being had to the accompanying drawings forming part hereof, in which:

25 Figure 1 is a side view of my invention partly in section and partly in elevation. Fig. 2 is a front elevational view of the invention. Fig. 3 is a detail vertical cross section of one of the air receptacles and the fan therefor. Fig. 4 is a detail plan view of the propelling and steering mechanism.

The air-craft generally designated in the drawings as *a* consists of a body *b* and a superstructure *c*. The superstructure *c* is made up of a series of air-domes 5 which are annular in shape and are closed at their upper ends. These air domes are formed of a substantially resilient material such as the canvas covering 6, which is enabled to retain its shape by means of the hoops 7. These hoops are provided both on the interior and the exterior of the canvas, at points adjacent to the ends of vertical walls of the same. Uprights 8 are provided which are assisted by the cross pieces 9 in preventing the canvas from ballooning abnormally when under pressure.

50 Struts 10 are provided with bifurcated upper ends which support adjoining air-domes. These struts are connected to the air domes at points alining with the hoops 7, and are secured thereto by means of the bolts 11. This form of connection admits of the domes being detached from the craft for repairing or other reasons.

A platform 12 is carried by the struts, and is spaced from the body *b* so that the operator of the craft may be within reach of the motors 13 which are depended from the under side of the platform, and are in vertical alignment with the domes 5. Connected to the motors 13 by suitable gearing 14, is a shaft 15. This shaft is vertically disposed and is centrally positioned in relation to the air dome which alines therewith. A brace-bar 16 is carried by the struts, adjacent to the air domes and functions as a bearing for the shafts 15. Positioned at the upper end of each shaft, is a fan 17 which is operated by a motor 13 and these fans are mounted so that an equal number thereof will rotate in opposite directions.

The motors 13 are centrally controlled from the seat of the operator and are simultaneously started or any single motor may be regulated when the occasion arrives.

It will be seen by referring to Figs. 1 and 3 that approximately half of the fan is inserted in its air dome. The fans when rotated, will tend to fill the domes with air, and in a short time the air stored up in the dome, will be under pressure, thus imparting an ascending motion to the craft. As the air fills the dome, it is obvious, that the fan will not force any additional air thereinto, but will displace the air in the immediate vicinity thereof, and thus lift the entire structure from the ground.

When the desired altitude is reached by the craft, the speed of the fans is diminished, and obviously, the result of this action will be to lessen the pressure on the air contained in the air dome. All the time any air is in the dome the tendency of such air will be to escape to the atmosphere, through vents 18 in the tops of the domes; but this escape, while the fans are being rotated at the usual operating speed, will be relatively small. Thus when the speed of the fans is lessened, the volume of air forced into the domes by the fans, is reduced. At a certain speed of rotation the lifting effect will neutralize the attraction of gravity, and the craft may be in a stationary position in the atmosphere. When it is desired to descend, the fans are retarded to a minimum and the domes will function as parachutes, causing the craft to glide to earth.

The body *b* is boat-shaped in structure which admits of its riding upon water. A

propeller 19 is provided at the rear of the body and is operated by a motor 20, for propelling the air-ship when in water.

Located at the forward or bow portion of the body is a Z-shaped frame 21, provided for carrying the air-propelling and steering mechanism *d*. This frame is pivotally mounted as at 22 and is adapted to be swung laterally for steering the ship. At the end 10 of this frame is a pair of propellers 23-23 which are geared to rotate in opposite directions, and are operated by means of the sprocket and chains 24 and 25 by the motor 26 mounted at the lower arm of the Z-shaped frame. A clutch 28 is provided, whereby the propellers may be in direct control of the operator. As shown in Fig. 4, the lower arm 27 of the frame is of greater width than the remainder of the frame, and provides 15 a base for the motor. The end of this base is provided with teeth 29 which mesh with a pinion 30. This pinion is connected to the steering wheel 31 by a universal joint indi-

cated conventionally at 32, by which means the pinion may be rotated for swinging the 25 frame 21.

As shown in Fig. 1 the space between the body *b* and the platform 12 may be inclosed by suitable material, such as canvas or tarpaulin cloth 33, which may be provided with 30 transparencies 34, thus forming a closed compartment for the operator and passengers.

What is claimed as new is:

In an air ship the combination of a cylindrical air dome and a fan arranged to discharge air thereinto, said air dome having its upper end closed by a closure disposed parallel with the path of movement of the fan, said closure being provided with vents. 35

In testimony whereof I affix my signature in presence of two witnesses.

DAVID LEVY.
